CLAIM

The ornamental design for a connector shell assembly, as shown and described.

DESCRIPTION

FIG. 1 is a first perspective view of a first element of a connector shell assembly showing my new design; FIG. 2 is a second perspective view of the first element thereof;

FIG. 3 is a front view of the first element thereof;

FIG. 4 is a back view of the first element thereof;

FIG. 5 is a left side view of the first element thereof;

FIG. 6 is a right side view of the first element thereof;

FIG. 7 is a top view of the first element thereof;

FIG. 8 is a bottom view of the first element thereof;

FIG. 9 is a perspective view of a second element of a connector shell assembly showing my new design;

FIG. 10 is a front view of a second element thereof;

FIG. 11 is a back view of the second element thereof;

FIG. 12 is a left side view of the second element thereof;

FIG. 13 is a right side view of the second element thereof;

FIG. 14 is a top view of the second element thereof;

FIG. 15 is a bottom view of the second element thereof;

FIG. 16 is a perspective view of the connector shell assembly in an assembled state showing the first and second elements thereof; and,

FIG. 17 is an exploded view of the connector shell assembly thereof.

The broken lines shown in the drawings depict portions of the connector shell assembly that form no part of the claimed design.

1 Claim, 17 Drawing Sheets
